UNITED STATES PATENT OFFICE

2,571,894

FLUID SHUTTER FOR LIGHT-PROJECTING APPARATUS

Jeremiah D. Kennelly, Oak Park, Ill.

Application March 12, 1948, Serial No. 14,574

1 Claim. (Cl. 116—114)

1

This invention relates to a fluid shutter for light-projecting apparatus. The invention is particularly useful in conjunction with the headlights or illumination lights of locomotives, train lights and lights used with emergency vehicles, aeroplanes, vessels, and other moving vehicles.

An object of the invention is to provide a fluid shutter effective for converting the illuminating rays from a searchlight, headlight or other light source into a warning light, etc. A further object is to provide a simple device which may be operated manually or automatically upon the drop in pressure in a brake pipe for the changing of projected light beams into warning light beams, etc., or into beams of various other colors for different purposes. Other specific objects and advantages will appear as the specification proceeds.

The invention is illustrated, in a single embodiment, by the accompanying drawing, in which—

Figure 1 is a side view in elevation of apparatus embodying my invention, the valve structure being shown in section; Fig. 2, a top plan view; and Fig. 3, an enlarged transverse sectional view of the fluid shutter, the shutter being shown in a preferred arrangement in front of a light source.

In the illustration given, 10 designates a reservoir tank, preferably closed at its top and with a conduit 11 leading to the bottom of a fluid filter 12. The fluid filter may be formed of any desired material and in any desired configuration.

In the illustration given, I provide a cylindrical frame 13 receiving therein, in spaced relation, the transparent plates 14 formed of glass, plastic or other suitable material, and providing between them a fluid chamber 15 adapted to receive a translucent colored fluid. The frame 13 is preferably provided with a ring 16 of resilient material, such as, for example, rubber, and with annular slots formed therein to receive the plates 14.

A conduit 17 leaves the top of the fluid shutter 12 and passes through a solenoid-operated valve 18. In the illustration given, the valve 18 consists of a rotary plug member 19, having a passage 20 extending therethrough, and received within a casing 21. The casing 21 is provided with an outlet vent 22 and with an outlet receiving a pipe 23 leading to the compressed air brake conduit, or to any other source of air pressure. The valve plug 19 may be rotated by hand

2

or, as illustrated, it may be rotated by a solenoid 24. By rotating the valve plug 19, the passage 20 therein may be brought into communication with the vent 22 or, alternatively, into communication with the brake pipe 23, as shown more clearly in Fig. 1.

The fluid filter may be located in front of the searchlight, headlight, train light, or any other light source which is ordinarily used for projecting light beams, and the passage of colored fluid into the chamber 15 brings about a change in the color of the projected light rays.

Any red liquid, which is pervious to the light rays, may be employed. Water colored red, or any other desired color, may be used. In order to avoid freezing of the liquid, any of the well-known liquids which do not freeze at low temperatures, may be used for this purpose, and any suitable coloring material may be employed.

20 In the specific illustration given, when the valve plug 19 is turned to the position illustrated in Fig. 1, compressed air from the brake pipe 23 passes through the valve, pipe 17, and fluid shutter 12, and forces the colored fluid out of chamber 15 and back through pipe 11 into the reservoir tank 10. The liquid is pressed upwardly in the tank 10 so as to compress the air trapped therein within the space indicated by the numeral 25.

25 The light source, which may be of any suitable type, is at this point effective merely for illumination purposes. In Fig. 3, a light-projecting casing 26, equipped with a light bulb 27, is located behind the fluid shutter 12, and when the chamber 15 is open, the light rays pass, without modification, through the transparent panes 14.

30 When it is desired to render the shutter operative for screening out the light rays or for changing their color, the valve plug 19 is rotated to bring the passage 20 into communication with the vent 22 and pipe 17. Upon the escape of the compressed air, the liquid within reservoir tank 10 will pass rapidly downwardly through pipe 11 and upwardly into chamber 15 to substantially fill the chamber. The latter movement of the liquid is accelerated by reason of the pressure exerted by the trapped air in space 25 of tank 10. The light rays now projected through the panes 14 and the body of fluid are changed in color. If a red fluid should be employed, the rays will thus become warning rays, etc.

35 As above stated, the valve plug 19 may be rotated manually or by actuating the solenoid 24. Further, if pipe 23 is connected to a brake pres-

sure line and the pressure falls below a predetermined limit, the liquid will flow against the reduced pressure upwardly into the chamber 15 of the fluid shutter 12 so as to automatically convert the projected light rays into warning rays.

While, in the foregoing specification, I have shown a single structure and described the same in considerable detail, it will be understood that the details of such structure may be varied widely by those skilled in the art without departing from the spirit of my invention.

I claim:

In combination with a light source carried by a vehicle equipped with a compressed air line, the compressed air line being used for setting brakes, a fluid shutter mounted in front of said light source and equipped with transparent plates providing a chamber between them adapted to receive a colored fluid, an air-tight reservoir adapted to receive said colored fluid, a conduit connecting said reservoir and said chamber, means supporting said reservoir at a level at least equal to that of said chamber, a valve casing equipped with a vent outlet, an outlet conduit communicating with the compressed air line, and

10

15

25

an outlet conduit communicating with the interior of said chamber, a valve in said casing having a passage establishing communication between said chamber and said vent pipe and alternatively between said chamber and said compressed air line, and solenoid control means for the valve operable to shift the valve to either position.
